UNITED STATES PATENT OFFICE.

DAVID J. SEAMAN, OF SOUTH BEND, INDIANA.

DESIGN FOR FABRIC.

SPECIFICATION forming part of Design No. 34,462, dated April 30, 1901.

Application filed April 8, 1901. Serial No. 54,955. Term of patent 14 years.

To all whom it may concern:

- Be it known that I, DAVID J. SEAMAN, a citizen of the United States of America, residing at South Bend, in the county of St. Joseph and State of Indiana, have invented and produced a new and original Design for Fabrics, of which the following is a specification, reference being had to the accompanying drawing, forming a part hereof.
- 5 10 15 20
- This design relates to the ornamentation of cotton, silk, woolen, paper, celluloid, and other fabrics.
- In the drawing I have shown a plan view of my design.
- The leading feature of the design is the representation of a holly leaves and berries running continuously along or upon the surface of the fabric in a compound curve, with straggling sprays of leaves and berries extending therefrom at intervals. The leaves
- A appear compactly along a compound curve, and the berries B are seen between the edges of the leaves. Occasional glimpses of stems C are shown along the outer edges of the leaves. Springing outward from the convex portions of the curve described by the leaves A are short sprays E, having a straggling appearance and directed generally toward the adjacent concave portions of the curve.
- What I claim is—
The design for a fabric herein described and shown.
- In testimony whereof I have signed this specification in the presence of two attesting witnesses.

DAVID J. SEAMAN.

Witnesses:

ALMEDA DICE,
CLARA B. SHULTZ.
